UNITED STATES PATENT OFFICE.

WILLIAM J. BRACKNEY, OF COYLEVILLE, PENNSYLVANIA.

WASHING-MACHINE.

SPECIFICATION forming part of Letters Patent No. 431,323, dated July 1, 1890.

Application filed March 14, 1890. Serial No. 343,939. (No model.)

To all whom it may concern:

Be it known that I, WILLIAM J. BRACKNEY, of Coyleville, in the county of Butler and State of Pennsylvania, have invented a new 5 and Improved Washing-Machine, of which the following is a full, clear, and exact description.

This invention relates to improvements in washing-machines, and has for its object to 10 produce a durable and efficient device of the character named, compact in form and of cheap construction, and which will be convenient in use.

To these ends my invention consists in certain 15 features of construction and combinations of parts, as will be hereinafter described, and indicated in the claims.

Reference is to be had to the accompanying drawings, forming a part of this specification, 20 in which similar letters of reference indicate corresponding parts in all the figures.

Figure 1 is a side elevation, in section, of the device, taken on the line 1 1 in Fig. 2. Fig. 2 is a transverse section of the machine, 25 taken on the line 2 2 in Fig. 4. Fig. 3 is a plan view of a detachable folding frame used to support the machine when in use, the outline of which is shown in dotted lines. Fig. 4 is a plan view of the device with the top 30 rubber-frame and its operating-levers removed. Fig. 5 is an inverted plan view of the upper rubber-frame; and Fig. 6 is a side elevation of the upper rubber-frame with attached standards, by which it is moved.

35 This machine is of the reciprocating rubber type, two oppositely-moving rubbers being employed, which engage articles to be washed that are placed between them, as will be more fully described.

40 The suds-box A is preferably made rectangular, of proper dimensions for its use, having a close bottom a and transverse bottom ledges a', placed at the ends on the bottom, the use of which will appear.

45 Within the box A re-enforce walls b are secured, which are separated a suitable distance near the longitudinal center of the box to afford space for vibration of the upright 50 rocking levers c, which are located in elongated recesses or sockets formed by the attachment of thin covering-plates d upon the

inner vertical edges of the re-enforce walls. The rocking levers c are secured together at their upper ends by a cross-bar c', which serves as a grip-piece to vibrate the levers 55 and operate the rubber-frames of the machine, and are journaled in the sides of the suds-box A at c".

The lower rubber-frame is considerably shorter than the suds-box, and is comprised 60 of a center guide-bar e and side bars f, which are equally spaced from the guide-bar e, they being connected to the same and each other by the rubber-strips g, which latter are of a number sufficient for the capacity of the machine, and are held spaced in series transversely of the guide-bar e by their attachment to it and the side bars f, thus producing a rectangular slatted frame, through which the suds-water may circulate when the 65 frame is moved. Preferably the series of rubbing-strips g are each made a quarter-cylinder in cross-section, so disposed that their rounded sides will face toward the opposite ends of the suds-box from the longitudinal 70 center of the frame.

Upon the interior bottom surface of the suds-box A two stationary guide-bars h are secured. These, having loose contact with the sides of the guide-bar e, are proportioned in 80 breadth to afford longitudinal grooves between them and the re-enforce walls b, in which the side bars f of the bottom rubber-frame may reciprocate.

Aligning holes are formed in three rows 85 through the rubbing-strips g, said rows of perforations being located at spaced intervals, laterally considered, and directly above the center guide-bar e for the loose support of the cylindrical guard-rods i, which rods fit 90 loosely against each end of the suds-box A, their office being to prevent clothes from wedging between the end of the guide-bar e and ends of the suds-box A, which would lock the rubber-frame from reciprocation that is effected by its pivotal connection with the lower ends of the rocking levers c, by the pivots c' extending inwardly from the levers and engaging slots formed at the longitudinal center of the rubber-frame in the side bars f 100 thereof.

Above the guard-rods i transverse cleats i'

are attached to the end walls of the suds-box A, which loosely engage the ends of the rods and prevent small articles from working below them, and also hold the lower rubber-frame from being crowded up at either end when it is operated.

The upper rubber-frame (shown detached in Figs. 5 and 6) consists of a pair of side bars *m* of equal length with those on the lower rubber-frame, these being connected by the transverse rubbing-strips *n*, similar in form to that of the strips *g* on the lower frame, said strips being firmly secured by their ends to the side bars and also to the longitudinal guide-pieces *o*, that are of equal length with the side bars *m* and abut against them edge-wise, the upper surface of the joined pieces lying in the same plane. The guide-pieces *o* are of such width proportionately that a sufficient space between them will be afforded for the introduction of the center guide-piece *p*, that loosely engages the inner edges of the side guide-pieces *o*. The three pieces *o o p*, having equal thickness, are level on the upper surface. It is necessary that the center guide-piece *p* should remain stationary with regard to the rubbing-strips *n* and side guide-pieces *o o*, and also be retained central, laterally considered. To these ends the piece *p* is made to fit closely, but removably, between the end walls of the suds-box A, and on each end portion of the same the transverse cover-boards *r* are attached, these cover-boards being of suitable width to close the opening into the suds-box below when the upper rubber-frame is reciprocated, and of a length to fit loosely against the inside surface of the suds-box sides.

Near the longitudinal center of the side bars *m*, on the upper rubber-frame, two standards *s* are oppositely erected, their outer surfaces aligning with those of the side bars on which they are secured. The standards *s* are vertically slotted from a point *s'*, near their upper terminals, through their lower ends, these slots extending through the side bars *m*, also, to afford a free passage for the oppositely and inwardly projected pins *t*, that are affixed in the inner faces of the rocking levers *c* a short distance above the suds-box. To afford support to the standards *s*, a cross-bar *u* is secured between and to their lower ends, and also upon the side guide-pieces *o o* of the upper rubber-frame, and above the cross-bar *u* a handle-bar *v* is likewise attached to the inner faces of the standards *s* across the slots in the same.

At proper points slots are formed in the end walls of the suds-box A, in which are pivoted the turn-buckles *w*, that may be projected within the box, as shown in Fig. 1, or be withdrawn from the same, as occasion may require, similar turn-buckle latches *w'* being secured on the edges of the end walls above those first named.

In operation the turn-buckles *w* are made to align with the end walls of the suds-box A,

so that the upper rubber-frame may adjust itself vertically within the box upon the material to be cleansed, and when a full box is to be operated upon the goods are placed therein until they must be slightly compressed by the upper rubber-frame, when it is placed on the stops or turn-buckles *w* and held thereon by the upper turn-buckles *w'*.

It is apparent that a vibration of the rocking levers *c* will actuate the upper and lower rubber-frames of the machine in opposite directions by reason of their pivotal connection thereto above and below the pivot-supports *c'* of said levers, so that a rubbing action of the strips on these frames is had upon the material placed between them and a longitudinal agitation of the goods and suds-water also, which will cause a penetration of water through the clothes and rapid removal of impurities therefrom.

There is a folding frame B provided for the support of the suds-box A when in operation. This consists of four uprights *x*, having hook-shoulders *x'* formed on their upper portions facing toward each other in pairs. Said uprights *x* are held spaced apart the width of the suds-box A by transverse stretcher-rods *x*², secured in the same near their upper and lower ends, and upon the lower pair of transverse stretcher-rods two pairs of locking-bars *y* are pivoted. The bars *y* are of such a length proportioned to that of the suds-box that when the uprights *x* are hooked upon the ends of the longitudinal cleats *x*³ on the suds-box and the upper stretcher-rods *x*² bear against the transverse batten ledges *a'*, so as to give the uprights a vertical position, these locking-bars *y* will lie inclined from the points *y'*, where they pivotally engage the cross-bar *y*², toward the lower stretcher-rods and be enabled to spread the lower portion of the folding frame B endwise when they are depressed.

Upon the cross-bar *y*² a pawl *y*³ is loosely mounted, which may engage the ratchet-rack *y*⁴, formed on or secured to the bottom *a* of the suds-box A and hold secure the locking-bars *y* at any point of depression given thereto, which adjustment of parts will secure the folding frame B upon the suds-box A and permit its disengagement in an obvious manner.

When the frame B is not in use, it may be folded so as to take up but little space by swinging the uprights *x* so as to bring them together, the locking-bars *y* lying between the stretcher-rods so that the parts may be arranged compactly when not in service.

Having thus described my invention, what I claim as new, and desire to secure by Letters Patent, is—

1. The combination, with a rectangular suds-box, two oppositely-pivoted rocking levers connected by a cross-bar, and an upper rubber-frame having slotted standards which are engaged by studs on the rocking levers, of a lower rubber-frame having open slots which are engaged by pivot-studs on the lower

end of rocking levers, substantially as set forth.

2. In a washing-machine having two rubbing-frames oppositely reciprocated, a lower rubber-frame comprised of two side bars, a series of transverse rubbing-strips spaced apart on the side bars, a center guide-bar, and spaced longitudinal guard-rods that loosely engage perforations in the rubbing-strips, substantially as set forth.

3. In a washing-machine having two oppositely-moved rubber-frames, the combination, with two longitudinally-located guide-pieces affixed to the inner surface of the rectangular suds-box and said rectangular suds-box, of a lower rubber-frame comprised of two side bars, a series of transverse rubbing-strips, a center guide-piece, guard-rods that engage holes in the series of rubbing-strips, and rocking levers which are adapted to reciprocate the lower rubber-frame, substantially as set forth.

4. In a washing-machine having a rectangular suds-box and two rubber-frames which

move in opposite directions, an upper rubber-frame comprised of two side bars, a series of spaced rubbing-strips, side guide-pieces attached longitudinally on the rubbing-strips, a center guide-piece, a transverse cover-board secured on each end of the center guide-piece, and oppositely-located upright slotted standards which are attached to the side bars and are pivotally engaged by rocking levers that actuate the upper rubber-frame, substantially as set forth.

5. In a washing-machine, the combination, with a suds-box and levers pivoted to the sides thereof, of a lower rubber-frame held to slide in the suds-box and pivoted to said levers, an upper rubber-frame adjustably pivoted to said levers, and a guide-frame for said upper rubber-frame, substantially as shown and described.
